(57) **CLAIM**

The ornamental design for a combination cooling and charging station for gaming, as shown and described.

DESCRIPTION

FIG. 1 is a front perspective view of a combination cooling and charging station for gaming showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The broken lines depict portions of the combination cooling and charging station for gaming that form no part of the claimed design.
